UNITED STATES PATENT OFFICE.

PETER STUDER AND PETER RUPP, OF WHITEHOUSE, OHIO.

ROTARY ENGINE.

SPECIFICATION forming part of Letters Patent No. 708,937, dated September 9, 1902.

Application filed May 31, 1902. Serial No. 109,725. (No model.)

To all whom it may concern:

Be it known that we, PETER STUDER and PETER RUPP, residing at Whitehouse, in the county of Lucas and State of Ohio, have invented a new and Improved Rotary Engine, of which the following is a specification.

Our invention more particularly refers to improvements in that type of rotary engines the construction of which includes a plurality of annular steam-chambers, a single drive-shaft common to both chambers and having a concentrically-disposed piston-carrying disk for each chamber, a valve-controlled steam-inlet and an outlet for each chamber, a separate abutment for coöperating with each piston-disk, and means controlled by the drive-shaft for shifting the abutments controlling the valves and governing the feed of the live steam to the steam-chambers.

Our invention in its generic nature comprehends a new and novel arrangement of a casing having two annular steam chambers or cylinders, two disks, two abutments, a single drive-shaft having means for controlling the shiftable movement of the abutments, and a governor for each valved feed-inlet to the steam-chambers; and in its more subordinate features it consists in certain peculiar detailed arrangement and novel combination of parts, all of which will hereinafter be fully explained, and specifically pointed out in the appended claims, reference being had to the accompanying drawings, in which—

Figure 1 is a side elevation of our improved rotary engine, the feed-valve devices being adjusted to lead the live steam into the cylinders to rotate the shaft and its piston-carrying disks in the direction indicated by the arrow *a*. Fig. 2 is a transverse section of the engine on the line 2 2 of Fig. 1. Fig. 3 is a vertical longitudinal section of the same on the line 3 3 of Fig. 2 looking in the direction of the arrow *b*. Fig. 4 is a cross-section, on an enlarged scale, of the upper end of the two cylinders and the steam-chests therefor, taken on the line 4 4 of Fig. 1. Fig. 5 is a detail sectional view on line 5 5 of Fig. 2 looking in the direction of arrow *a*, illustrating the governor mechanism. Fig. 6 is a similar view of the same mechanism, showing the position of the parts when the engine is running at excess speed. Fig. 7 is a detail horizontal section

taken substantially on the line 7 7 of Fig. 1. Fig. 8 is a detail view illustrating the correlative arrangement of the drive-shaft, the piston-disks, and the oppositely-disposed pistons. Figs. 9 and 10 are longitudinal and transverse detail sections illustrating the manner in which the pistons are attached to the piston-disk.

In the practical construction of our engine the cylindrical portion or casing is suitably mounted upon a bed *B*, supported upon a brick foundation, upon which the bed *B* is anchored in any suitable manner. The casing comprises a central portion *A*, having a cylindrical bore *a*, and head members *a' a'*, fastened to the portion *A* in any suitable manner and curved, as at *a'x*, to provide the spaces *x* to receive the piston-disks *b b*, fixedly mounted on or formed integral with the disk-hub *b'x*, they being for conveniently adjusting them secured to the disk-hub *b'x* by bolts *b'3*, as clearly shown in Figs. 4, 9, and 10. Upon each end of the casing is mounted an annular enlargement *C*, each consisting of two half-sections circumferentially flanged to receive the fastening-bolts and having base-flanges for conveniently connecting them steam-tight to the casing, as best shown in Fig. 4, 80 by reference to which it will be noticed each annular enlargement has an inner annular steam-chamber *C'* in line with the annular space in which the pistons rotate and a steam-jacket *C'2* surrounding the chamber *C'* for reasons presently explained.

As will be readily understood by reference to Fig. 4, the peripheral edges of the piston-disks *b* terminate at the bottom of the steam-chambers *C'*, whereby to provide for snugly fitting the pistons *c c*, that travel in the chambers *C'*. In the present construction we have illustrated each piston-disk provided with a single piston *c* and these two pistons disposed at diametrically opposite points, as such arrangement of pistons is specially devised for coöperating with the valved steam feed and exhaust mechanisms, hereinafter explained.

To provide for a tight steam-joint between the chambers *C'* and the spaces *x*, where the necks of the pistons pass over the joint between said chambers *C'* and spaces *x*, the neck portions of the piston-disks are beveled, as at *b'5*, to receive the triangular-shaped

metallic packing-rings D, seated in annular grooves c^5 in the casing A, as clearly shown in Fig. 4, and to provide for taking up wear the rings coöperate with adjusting screws and 5 springs c^6 , the screw projecting outside the casing for convenient manipulation.

The steam-jackets C² are fed by supplemental valved steam-pipes 10 10^a, and the said jackets have valved outlets for drawing 10 off the condensed steam and leading same back to the boiler. Each steam-chamber C³ has an attached steam-chest F, preferably located at the upper end of the casing, and each chest has two ports f f', that communicate with the steam-chamber. 15

A sliding abutment G is provided for each annular steam-chamber C³, which coöperates with the two inlet-ports f f' and their respective pistons c, and the said abutment G is disposed midway the ports f f', as best shown in Figs. 1, 2, and 3, from which it will be noticed the abutment G is joined with a frame g, vertically slideable on guideways g', projected horizontally from the casing-top and 20 normally held to its downward or closing position by the spring f². At one side each sliding frame has a lateral extension f³, with which connects a pendent arm f⁴, suitably guided and carrying a roller-bearing f⁵ at its 25 lower end, adapted to engage with the cam projections h of the lifting-disks H, fixedly mounted on the shaft exteriorly of the engine-casing and adapted at predetermined intervals to lift the abutment G out of the path of 30 the moving pistons. To provide for a proper impulse of live steam against the shaft alternately from the opposite steam-chambers, the cam-disks H are disposed so their cams h are relatively at diametrically opposite points. 35

40 Each steam-chest F has a circular valve-receiving casing 5 for each of the ports f f', and in each casing is mounted a semirotatable valve 5^a, having a channel-way 5^X, adapted under one adjustment to alternately open 45 up and close off communication between the steam-chest F and the chamber C³. Each valve 5^X has a stem 5^b, having a crank member 5^c, and the crank members of the two coöperating valves project toward each other 50 and are each provided with a pivotally-hung link 5^d, in turn pivotally joined to a single connecting member 5^e, that forms a part of a combined reversing and valve-operating means, the construction of which is best understood by referring to Figs. 1, 4, and 7, from which it will be seen the member 5^e has a longitudinal slot 5^X, in which slides a head 6^a, horizontally adjustable in a suitable guideway 6^b on the adjacent face of the casing. 55

60 The head 6^a is connected to a rod 6^c, connected with the shifting lever 6^d.

7 designates a lever pivotally connected to the under side of the member 5^e, centrally thereof, and having vertical movement in the 65 guide-brackets 7^a 7^b and operated by suitable eccentric or cam devices automatically

adjustable by the governor mechanism, presently referred to.

So far as described, when the piston and shaft are to be run in the direction indicated 70 the valve-setting mechanism is positioned as shown in Fig. 1, and with the head 6^a to the left of the vertical axis of the engine to provide a stationary fulcrum for the member 5^e and hold the valve that controls the steam-port f to an inoperative position and closing off the steam-chest F from the steam-chamber C³ through port f. When thus positioned, it is manifest when the rod 7 is vertically reciprocated, as presently described, the member 5^e will rock on the fulcrum 6^a and impart a semirotary motion to the valve that controls the port f' and open and close said port at predetermined times, the opening occurring when the piston has just passed the port 85 f' and the abutment is down to its closure position, the closing occurring just prior to the passing of the piston beyond the exhaust. 90

Each rod 7 has a special means for automatically reciprocating it at proper times. 90 One set of such means is shown in detail in Figs. 5 and 6 and consists in a disk 8, eccentrically mounted on the abutment-operating disk H and provided with an annular groove 8^a, with which the roller-bearing 7^b of the 95 member 7 engages. The fulcrum of the disk 8 is in the vertical axis or plane of the abutment, and the said disk 8 is also provided with a slot 8^b, curved on an arc with the fulcrum 8^X as the center for the passage of the drive-shaft, which acts as a guide for the swinging or gravitating end of the disk 8. The disk H is also provided with a concentric slot 8^d, in which plays the stud 9^a on the arm 9^X of the governor J, which consists of 100 bar 9, slotted at 9^c to ride on the drive-shaft in a radial direction. To automatically draw the bar 9 to its inner or normal position, a spring i is provided, made fast at one end to the disk H and at the other end to the arm 9^X. 110

12 designates a weight on the outer end of the stem 9^b of member 9. By reason of the peculiar construction of the disk 8 and the governor devices joined therewith it is apparent that under normal conditions the disk 115 8 is positioned relatively to the drive-shaft in such manner as to effect a maximum reciprocal movement of the valve that controls the steam inflow through the port f'. Now as the engine speeds up the governor member 9 by centrifugal force moves radially outward, thereby causing the disk 8 to rock, with its axial center toward the drive-shaft, and in consequence thereof reduce the eccentric or cam movement imparted by it to the member 120 7 and correspondingly shorten the stroke of the valve to port f' and proportionately cut off the steam-supply, it being understood that during operation the governor mechanism will readily control the inflow of steam and 125 maintain the running speed of the engine at an approximately uniform speed. 130

The pistons *c* consist of a disk having a laterally-projecting stud-axle *c*⁵, adapted to seat in the bearings 13^a of brackets 13, fixedly held or integrally formed as an integral part 5 of the disks *b*, and said stud-axles are yieldingly held on said bearings by the springs 17^a 17^b, as clearly shown in Fig. 3, such position of the disks providing for such slight irregularity of the annular steam-chamber and to maintain a proper correlative arrangement 10 of the said disks with the annular bores or chambers *C*³, and to still further provide for a steam-tight joint between the pistons *c* and the chambers *C*³ each piston *c* has a packing 15 ring 14^x.

15 designates a lever for cutting off the steam to the steam-jackets.

From the foregoing description, taken in connection with the accompanying drawings, 20 it is believed the general operation and the advantages of our construction of rotary engine will be readily understood by those skilled in the art to which it appertains.

By arranging the pistons diametrically opposite and the abutment-operating and steam-feed devices in the manner shown and described it is apparent that should the parts be in the position shown in Figs. 1, 2, and 3, the abutment to the chamber *C*², Fig. 3, being closed, the piston beyond the inlet *f*', and said inlet open, the live steam entering back of the piston by reason of its direct and expansive force impels the piston forward until it reaches a point diametrically opposite 30 that at which it appears in full lines in Fig. 3. When this position occurs, the abutment for the other annular chamber *C*² will be closed down and the steam-inlet to said chamber opened to force its piston forward as the 35 steam-inlet to the first-mentioned chamber *C*² closes. Thus the shaft will be under an impelling force of live steam at all times and little or no lost motion is incurred by reason of the shifting of the abutments and the steam-cut-off slides.

While we have shown but two annular chambers and piston and steam-feed controlling mechanisms therefor, it is obvious an additional chamber may be provided and the 40 abutments and steam-feed mechanisms be operated under a trihedral action—that is, shifted at each third of a rotation of the disk instead of one-half, as shown. We are aware that engines of this kind having sliding abutment and cut-off valve devices coöperating therewith and operable by mechanism in connection with the drive-shaft and in which the said mechanism is adjusted to effect an alternate operation of the steam-controlling 45 valves and the abutment have heretofore been provided. Our invention differentiates from engines embodying the generic features stated, so far as we know, in the peculiar construction of the pistons on the rotary disk, 50 manner in which the several parts of the engine-cylinder are coöperatively joined, and the special connection between the abutment-

shifting devices, the steam cut-offs, and the single connection joined therewith controlled by the cam on drive-shaft.

70

Slight changes in the several essential features stated may be made without departing from the scope of the appended claims.

Having thus described our invention, what we claim, and desire to secure by Letters Patent, is—

1. A rotary engine, comprising a casing having a plurality of annular steam-chambers, a single drive-shaft, said casing having a central bore, a disk rotatable within the bore, 80 said disk having radial oppositely-disposed pistons, one for each annular chamber, cam devices on the shaft, a sliding abutment and cut-off valve for each annular steam-chamber, a separate means for automatically moving 85 each abutment to its closure position, intermediate connections joining each abutment with one of the cam devices on the shaft, and connections joining the cut-off valve for each annular steam-space with its respective abut- 90 ment, all being arranged substantially as shown and for the purposes described.

2. In a rotary engine, as described, the combination with the casing, having an annular steam-chamber, circular in cross-section; 95 of a drive-shaft, a piston-carrying member mounted thereon, having a radial bracket, a piston-disk having a stub-axle, and a spring bearing on the bracket to receive the said disk, substantially as shown and for the pur- 100 poses described.

3. In a rotary engine, as described, the combination with the annular steam-chamber, the steam-jackets surrounding the same, the automatically-operating abutment, said chamber having a steam-inlet at each side of the abutment, and a single exhaust; a piston operating with the annular chamber, a valve-chest communicating with the inlets, an independently-operating shifting valve for 105 each inlet, a connection joining both valves, said connection including a rocking member, and a means for changing the fulcrum of said rocking member, whereby to throw one of the valves out of an operative condition, and the 110 other into an operative condition, and a cam mechanism on the drive-shaft for imparting a motion to the rocking member, for the purposes described.

4. The combination in a rotary engine of 120 the character described, with the annular steam-chamber, the sliding abutment, means for normally forcing the abutment to a closed position, the annular chamber having a steam-inlet at each side of the abutment, and a single exhaust; a piston operating in the said 125 annular chamber, an independent valve for each inlet for controlling the steam-feed therethrough, a cam-disk mounted on the shaft, and connections between the disk and the sliding abutment coöperatively arranged for lifting the abutment, and a second cam-disk rotatable with the first cam-disk, and connections joining the second cam-disk with

the rockable valve-operating member, for the purposes described.

5. In a rotary engine of the character described, the combination with the annular steam-chamber, the automatically-operating sliding abutment, said chamber having an inlet at each side of the abutment; the steam-chest common to both inlets, an independent valve for each inlet, mounted in the said chest, a changeable cam-disk connected with the inlet-controlling valves, and a governor mechanism for controlling the changes in the valve-operating cam-disk, for the purposes described.
- 15 6. The combination with the annular steam-chamber, the piston, the automatically-operating abutment, said piston having a pair of inlets, one at each side of the abutment, a valve-chest communicating therewith, a sep-

arate valve for each inlet, each valve including a crank member, pivoted link connections joining both crank members, a rocker-arm including the said pivoted link connections, a shiftable fulcrum for the said rocker-arm, a cam disposed eccentrically of the drive-shaft and mounted to rotate with the said shaft, a link-arm joining the said eccentric with the valve-controlling mechanism, and a centrifugal governor for changing the position of the said eccentric, all being arranged substantially as shown and for the purposes described.

PETER STUDER.
PETER RUPP.
